(57) **CLAIM**

The ornamental design for a speaker pod, as shown and described.

DESCRIPTION

FIG. 1 is a top, front, right side perspective view of a speaker pod according to an embodiment of the present disclosure; FIG. 2 is a front elevation view of the speaker pod shown in FIG. 1;

FIG. 3 is a rear elevation view of the speaker pod shown in FIG. 1;

FIG. 4 is a left side elevation view of the speaker pod shown in FIG. 1;

FIG. 5 is a right side elevation view of the speaker pod shown in FIG. 1;

FIG. 6 is a top plan view of the speaker pod shown in FIG. 1; and,

FIG. 7 is a bottom plan view of the speaker pod shown in FIG. 1.

A second embodiment of a speaker pod according to the present disclosure is for a speaker pod that is a vertical axis mirror image of the speaker pod shown in FIGS. 1-7. FIG. 8 is a top, front, right side perspective view of the speaker pod of the first embodiment with the speaker pod of the second embodiment.

The broken lines in the drawings are included to show portions of the article that form no part of the claimed design.
